DESIGN FOR A PILLOW CASE OR SIMILAR ARTICLE

Edith N. Milliken, Wellesley, Mass., assignor to Nashua Manufacturing Company, Boston,
Mass., a corporation of New Hampshire

Application August 14, 1935, Serial No. 58,120

Term of patent 14 years

To all whom it may concern:

Be it known that I, Edith N. Milliken, a citizen of the United States, residing at Wellesley, in the county of Norfolk and State of Massachusetts, have invented a new, original, and ornamental Design for Pillow Cases or Similar Article, of which the following is a specification, reference being had to the accompanying drawing, forming a part thereof.

In the accompanying drawing,

Fig. 1 is a perspective view of a pillow case showing my design; and

Fig. 2 is a perspective sectional view of the pillow case shown in Fig. 1, bringing out the details of the design.

The design involves the hem portion of the pillow case but it is contemplated that the design may also be embodied in or applied to sheets and other similar articles.

I claim:

The ornamental design for a pillow case or similar article, substantially as shown and described.

EDITH N. MILLIKEN.
